UNITED STATES PATENT OFFICE.

WILLIAM M. HASBERG AND AXEL W. SWANLUND, OF CHICAGO, ILLINOIS, ASSIGNEES
TO SEARS, ROEBUCK AND COMPANY, OF CHICAGO, ILLINOIS, A CORPORATION OF
NEW YORK.

APPARATUS FOR CONVEYING AND DISTRIBUTING PAPERS AND THE LIKE.

1,157,865.

Specification of Letters Patent.

Patented Oct. 26, 1915.

Application filed March 14, 1914. Serial No. 824,607.

To all whom it may concern:

Be it known that we, WILLIAM M. HASBERG and AXEL W. SWANLUND, citizens of the United States, residing at Chicago, in the county of Cook and State of Illinois, have invented certain new and useful Improvements in Apparatus for Conveying and Distributing Papers and the like, of which the following is a specification.

10 This invention relates to improvements in apparatus for conveying letters, merchandise orders and other papers from a given point to a plurality of stations (which stations may be the desks of clerks among whom 15 the work of handling the orders or other papers is divided upon a geographical or other basis) and, if desired, for returning the papers to the starting point, for filing.

20 The object of the invention is to simplify the means for conveying the papers, and to prevent the papers from fouling on any part of the apparatus.

25 In the accompanying drawings, Figure 1 is a side elevation of the apparatus embodying the features of our invention, parts being broken away to shorten the view. Fig. 2 is a transverse vertical sectional view taken in the plane of dotted line 2 of Fig. 1. Fig. 3 is a view taken in the plane of dotted 30 line 3—3 of Fig. 1. Figs. 4 and 5, taken together, constitute a top plan view of the apparatus.

The embodiment herein shown of our invention is an elongated apparatus arranged 35 to extend between two rows of desks or other stations. The framework 1 of the apparatus may be of any suitable or preferred construction. Upon the framework is supported a horizontal table 2 extending longitudinally of the apparatus and provided 40 with a plurality of longitudinal partitions 3. The partitions 3 are sufficient in number to provide a passageway or guideway 4 for each receiving station. These stations are 45 located at opposite sides of the apparatus and at different distances from the head end of the apparatus, the length of each passageway corresponding to the distance between the head end of the apparatus and the respective stations. To produce this difference 50 in the length of the passageways, the partitions 3 are made of the proper length, as indicated in Figs. 4 and 5, and the table 2 is cut away so that the bottom of each

passageway terminates opposite its respective station. 55

Each passageway 4 is of such width that single papers or bunches of papers fastened together shall stand on edge in a substantially vertical position when placed in the 60 passageway. It will be understood that if a single sheet bends sufficiently so that a portion of its surfaces lies in contact with the bottom of the passageway, the larger part of the sheet is nevertheless substantially upright. 65

The means for moving the papers through the passageways 4 comprises a conveyer consisting of an endless chain or other suitable flexible cable or connector 5, said chain 70 running over sprocket wheels 6. Certain of these sprocket wheels are arranged so that the upper reach of the chain extends longitudinally of and above the table 2 and midway of the table. Suitable pusher members 75 such as rods 7 are secured to the chain 5 at suitable intervals, said pusher members extending transversely of the table and being carried by the chain above the partitions 3. The distance of the pushers 7 from the bottoms of the passageways 4 is such that the 80 pushers engage the papers at about midway of the height of the papers. It will be seen that as the chain 5 moves, the papers will be pushed through the passageways 4. 85

Any suitable means may be employed for driving the chain 5. Herein we have shown a motor 8 having a driving connection with a sprocket wheel 9 (Fig. 3) over which the chain is arranged to run. 90

Below the table 2 is a horizontal receiving table 10, extending longitudinally of the apparatus, to receive the papers which fall from the ends of the passageways 4. If desired, the clerks at the receiving stations may each be provided with a basket or tray (not shown) which may be placed upon the table 10 in position to receive the papers discharged from the respective passageways 4. 100

If desired, means may be provided for returning papers from the receiving stations to the head end of the apparatus. For this purpose, one or more passageways 11 may be provided below the table 10, said passageways extending longitudinally of the apparatus and adjacent to the sides of the framework 1 within convenient reach of the 105

clerks at the receiving stations. To move the papers through the passageways 11, the lower reach of the chain is supported to travel adjacent to the plane of said passageways so that the pushers 7 shall engage the papers in the passageways 11 about midway of the height of the papers. Any suitable means may be provided at the head end of the apparatus to receive the papers discharged from the passageways.

It will be seen that by our invention a single conveying element, namely, the chain 5, is arranged so as to convey papers through a plurality of passageways. It will also be seen that the passageways contain no spaces or crevices in which the papers may foul. Moreover, the movement of the papers through the passageways is more nearly positive than when the papers rest upon conveyer belts or the like.

We claim as our invention:

An apparatus for conveying papers and the like having, in combination, a plurality of upwardly opening passageways adapted to receive and guide papers or the like, said passageways terminating at different distances from the head of the apparatus to discharge the papers at different receiving

stations, means beneath said passageways to receive the discharged papers, a lower return passageway beneath said receiving means, guide wheels at opposite ends of the apparatus, an endless sprocket chain passing around said guide wheels with its upper run above the upper passageways, and with its lower run above the lower passageway, the upper and lower runs of the chain being in approximately the same vertical plane, means for driving said chain, and a plurality of cross pins carried by said chain, the pins at the upper run of the chain being adapted to engage the papers in the upper passageways and move them toward the receiving stations while the pins in the lower run of the chain are adapted to engage the papers in the lower passageway and move the papers in the opposite directions to the head of the apparatus.

In testimony whereof we hereunto set our hands in the presence of two witnesses.

WILLIAM M. HASBERG.
AXEL W. SWANLUND.

In the presence of—

NICHOLAS A. WEILAND,
EDNA LEIGHTON.
